UNITED STATES PATENT OFFICE.

FRED GIERSE, OF BEAUMONT, TEXAS.

WELL-DRILLING BIT.

Application filed May 5, 1920. Serial No. 379,125.

To all whom it may concern:

Be it known that I, FRED GIERSE, citizen of the United States, residing at Beaumont, in the county of Jefferson and State of Texas, have invented certain new and useful Improvements in Well-Drilling Bits; and I do hereby declare the following to be a full, clear, and exact description of the invention, such as will enable others skilled in the art 10 to which it appertains to make and use the same.

This invention relates to new and useful improvements in drilling bits and more particularly to a bit especially adapted for well 15 drilling, the main object of the present invention being the provision of a drilling bit used in drilling wells such as oil, gas and water wells and is so constructed that it is particularly adapted for drilling through 20 clay or what is commonly known as gumbo for cutting the material into fine particles so that it can be readily removed from the well being drilled through the means of water pressure or the like.

Another object of the present invention is 25 the provision of a drilling bit, the cutting edges of which are so arranged and provided with suitable guides whereby the drilling bit will work in a straight line perpendicular 30 to the earth's surface and thus prevent the bit from moving out of its line of travel so that when the casing of the well is set or removed, this operation can be carried out with very little trouble.

A further object of the invention is the 35 provision of a drilling bit having in connection therewith suitable means for supplying the same with water or the like to remove the particles of earth after they have been 40 crushed, up between cutting edges so as to thus prevent any clogging of the cutting edges by the accumulation of unnecessary material around the drilling bit.

With the above and other objects in view, 45 the invention consists in the novel features and construction, the combination and arrangement of parts hereinafter more fully set forth, pointed out in the claims and shown in the accompanying drawings, in 50 which—

Figure I is a side elevation of a drilling bit constructed in accordance with my invention,

Figure II is a similar view taken at right angles to the illustration in Figure I,

Figure III is a vertical sectional view, taken on the line III—III of Figure I,

Figure IV is a bottom plan view,

Figure V is a top plan view, and

Figure VI is a transverse sectional view 60 taken on the line VI—VI of Figure I.

In the construction of my improved bit, I provide a central body member, generally indicated by the numeral 1, the outer end of which is somewhat enlarged as shown at 2 65 and provided with screw threads 3, whereby the bit can be readily attached to a sleeve, pipe coupling or the like and readily removed should the occasion demand. Upon each side of the central body member 1, at 70 a point just below the enlarged portion 2, outwardly projecting webs 4 are formed upon diametrically opposite sides of the body, the outer edges of said webs terminating in suitable cutting blades 5, the outer ends of 75 which are arranged in spaced relation, as is clearly illustrated in Figures IV and V, and upon rotation of the bit, follow each other in a cutting circle. The cutting blades 5 are provided with suitable guides 6, which 80 tend to carry the pulverized material in toward the body member 1 where it is sucked up through suitable means for conveying the same from the bit which will be described 85 more fully hereinafter.

The body 1 is also provided with a second series of cutting blades, generally indicated by the numeral 7, these cutting blades 7 being arranged directly below the cutting blades 5 so that in cutting or pulverizing 90 the gumbo or other material, the material will be thoroughly pulverized by the action of the blades 7, together with the blades 5. These blades 7 are also provided with suitable guide wings 8 whereby the material 95 which has been cut by the blades 7 will be guided upwardly toward suitable removing means.

The lower end of the body member 1 is provided with a guide cutter, indicated by 100 the numeral 9, which is provided with two cutting edges and is formed by having opposite sides of the body 1 curved at its lower end to provide the oppositely disposed cutting edges 10. This guide cutter 105 9 penetrates the earth in advance of the cutters 7 and 5 and cuts a circle in the earth substantially smaller than the cutting blades 7. The material which is removed by the cutting edges 10 is forced up. 110

wardly between the guides 8 and upon the downward movement of the bit, the blades 7 will cut and remove the material in a circle slightly greater than the circle cut by 5 the member 9 and as the bit advances into the earth, the cutting blades 5 will then begin to operate upon the earth and cut a circle slightly larger than the circle which is 10 cut by the blades 5, being of the required diameter of the well being drilled.

In order to remove the pulverized material from the well being drilled, suitable pipes 11 are provided and arranged upon opposite sides of the body member 1 between 15 the webs 4 and securely retained in position by means of the clamp 12. The clamp 12, as herein illustrated, is U-shaped in form and adapted to embrace the pipe 6, the ends of said clamp having suitable 20 nuts 13, threaded thereon for engaging a washer plate 14, mounted upon the ends of the clamp 12 whereby the clamp is securely tightened against the pipes 11 to retain them in their proper relation to the body 25 member 1.

The upper ends of the pipes 11 are fitted into suitable openings 15 arranged within the enlarged portion 2 of the body 1 and as the portion 2 is connected with a sleeve or 30 pipe coupling, the pipes 11 will be arranged in communication with this sleeve, whereby water may be introduced to the drill bit for conveying the material from around the bit up through the sleeve and thus prevent 35 the accumulation of the pulverized material around the drill bit. It will be noted that the lower ends of these pipes 11 extend downwardly to a point below the upper ends of the guide members 8 so that the 40 loose material which is cut and pulverized by the cutting edges 7 and 10 can be readily washed up through these pipes 11 so as to keep the cutting edges clear from the accumulated material.

45 From the above description, taken in connection with the accompanying drawings, it will be readily apparent that I have provided a well drilling bit which is particularly adapted for drilling in clay or 50 other earth material of this character whereby the material will be thoroughly pulverized and removed from around the bits as soon as it has been pulverized to the required extent. It will also be noted that by 55 providing a plurality of cutting blades ar-

ranged so that a plurality of circles of various diameters is cut into the earth as the bit advances, the earth will be more thoroughly pulverized and cut into smaller particles than by having the cutting blades arranged so that they all descend within the same diameter. As stated heretofore, the guide member 9 with its cutting blades 10 cuts a small hole in the earth as the 60 drill bit advances, which forms a guide for the following bits and as the bit advances, the blades 7 cut a larger circle than the blades 10 and so on with the blades 5, and as this material is cut into the different sized circles, the water which operates 65 through the pipes 11 will carry off the pulverized material.

What I claim is:

1. A drill bit of the class described, including a central body portion having a guide cutter formed at its lower end, a plurality of cutting blades formed on the body adjacent the guide cutter, a second series of cutting blades formed on the body above the first series and disposed at an angle with respect thereto, conveyor pipes secured to the body and having communication with spaces between the cutting blades of the first series whereby to remove the material after being acted upon by the blades. 75

2. A drill bit of the class described, including a central body portion having a guide cutter formed at its lower end, a plurality of cutting blades formed on the body adjacent the guide cutter, a second series of cutting blades formed on the body above the first series and disposed at an angle with respect thereto, conveyor pipes disposed upon opposite sides of the body for 80 conveying the material acted upon by the cutters away from the bit, a U-shaped clamp adapted to embrace the pipes and body for retaining said pipes in position. 85

3. A drilling bit including a plurality of cutting blades, a second series of blades arranged above the first series and adapted to cut a larger circle than the first series and conveyor pipes having communication with spaces between the cutting blades of the first series whereby to remove the material 90 after being acted upon by the blades. 100

In testimony whereof I have affixed my signature.

FRED GIERSE.
